GEORGE W. BLANKENHORN, OF SAN FRANCISCO, CALIFORNIA; PAULINE E. WITHERBY
GUARDIAN OF THE ESTATE OF SAID GEORGE W. BLANKENHORN.

MACHINE FOR CORRECTING IRREGULARITIES IN FLANGES OF CANS PRELIMINARY
TO SEALING THE CANS.

Application filed July 31, 1922. Serial No. 578,594.

This invention relates to improvements in canning machinery and resides in the provision of a machine which will facilitate and increase the efficiency of canning apparatus particularly machines known as "syrupers" and "seamers".

In the handling of empty cans preliminary to canning operations, the open ends of the cans and the flanges are often bent or distorted and it has been the practice to correct such irregularities by hand in instances where such irregularities come to the attention of the operators. In a great many instances the irregularities escape notice with the result that when the cans are treated in the syruper the syrup spills and when the cans are sealed, poor or faulty seams are produced.

It is the primary object of the invention to provide a machine which will treat the cans as they are advanced to the syruper so as to correct irregularities in the flanges at the open ends of the cans whereby the syruper may be more effectively operated and tight and uniform seaming means will be provided, the operation of correcting such irregularities being such as will not interfere with the progress of the cans in their movement from one canning machine to the other.

The invention possesses other advantages and features some of which, with the foregoing will be set forth at length in the following description where I shall outline in full that form of the invention which I have selected for illustration in the drawings accompanying and forming a part of the present specification. In said drawings I have shown one form of the construction of my invention, but it is to be understood that I do not limit myself to such form since the invention as expressed in the claims may be embodied in a plurality of forms.

Referring to the drawings:

Figure 1 represents a top plan view of the apparatus of my invention;

Fig. 2 represents a side elevation of the apparatus parts being broken away and other parts being shown in section for the sake of clearness of illustration;

Fig. 3 represents an end elevation of the apparatus;

Fig. 4 represents an enlarged side eleva-

tion partly in section of a detail of the apparatus;

Fig. 5 represents a view at right angles to Figure 4 being partly in elevation and partly in section;

Fig. 6 represents an enlarged view in elevation and a vertical section of one of the devices for correcting the irregularities in the cans;

Fig. 7 is a view of an end elevation partly in section of one of the rollers for correcting irregularities; and

Fig. 8 is a side elevation of a can after the irregularities have been corrected.

Referring to the embodiment of the invention illustrated in the accompanying drawings 1 designates a table supported by suitable legs 2, and upon which the mechanism of my invention is mounted, said table being divided longitudinally to provide a space 3 in which the upper run of an endless conveyor 4 may travel. The conveyor 4 is provided with means 5 for engaging and moving the cans 6 along the usual guide members 7, which latter as well as the conveyor lead to and from the table. The operation of the conveyor and the arrangement of the guides is such as will cause cans to be advanced to the machine of my invention and from thence to the drainer and syruper not shown.

Similar mechanisms are arranged upon opposite sides of the table to engage the cans as the conveyor advances them to the machine of my invention, and support the cans while irregularities thereof are being corrected. Each of these mechanisms comprises a flexible endless carrier 8 in the form of a sprocket chain mounted upon sprockets 9 and 10. The sprockets are mounted upon upright shafts 11 and 12 journaled in bearings 13 mounted upon the table. The shafts 11 of the two mechanisms are provided with beveled pinions 14 on their lower ends, which pinions mesh with similar gears 15 carried upon the end of a shaft 16 journaled in bearings 17, which latter depend from the table. One of the pinions 14 meshes with a beveled gear 18 carried upon a drive shaft 19, which shaft is mounted on a suitable bearing 20 fixed to the table and has a pulley 21, providing for its being driven by a motor or other source of power not shown.

The arrangement of the two mechanisms as regards the driving thereof, is such that they are rotated in corresponding directions and in synchronism with the conveyor 4, 5 said mechanisms being located in the same horizontal plane.

- The chains or carriers 8 have fixed thereto at spaced points a plurality of can engaging and supporting blocks 22, each of 10 which is of substantially rectilinear outline and provided in its outer face with a semi-circular groove or channel 23. The blocks are preferably made of solid metal and so arranged that when the chains or carriers 15 8 are rotated, said blocks will advance towards one another at points adjacent the conveyor 4 and pairs of the blocks will encompass the cans as they reach a certain point along the conveyor, the opposed edges 20 of the blocks substantially engaging one another, as shown in Figs. 1 and 3. The blocks are so constructed that when engaged with the cans the flanges 24 of said cans will overlie the upper flat ends of the blocks. The 25 lower edges of the blocks are slidably engaged with the upper sides of the sections or halves of the table 1 as the conveyor is moved along with the chains over said table. Means is provided upon the table along 30 opposite sides of the space 3 for engaging the bottoms of the cans and causing said cans to be lifted upwardly as they are advanced into position to be engaged by the blocks. This means comprises longitudinal 35 shoes 25 having beveled forward ends 26 and which are normally held above the level of the table by springs 27, which springs engage in registering sockets 28 in the table and members 25 respectively. As the cans 40 encounter the beveled ends 26 they will rise and slide over the uppermost sides of the members 25 so that the flanges 24 will be disposed above the upper ends of the blocks engaging the cans.
- 45 Mounted upon the table is a means for correcting the irregularities in the cans at their open ends and on the flanges. This means comprises upright frame pieces 29 and 30 which are mounted on respective halves of 50 the table on opposite sides of the conveyor 4 and path of movement of the blocks 22. A horizontally mounted roller 31 is disposed between the members 29 and 30 upon a shaft 32 to which latter it is fixed. The shaft is 55 mounted in vertical adjustable bearing blocks 33, which latter are mounted in slots 34 in the respective frame pieces 29 and 30. The blocks 33 are engaged upon their under sides by adjusting screws 35 and upon their 60 upper sides by similar adjusting screws 36, both of which screws are provided with nuts 37 and 38 to regulate the positions of the blocks 33 and roller. An expansion spring 39 is mounted upon each of the screws 36 and 65 bears downwardly upon the block 33. The

roller 31 is cylindrical except for a protuberance or projection 40, which extends from a point central of the ends of the roller, at right angles of the longitudinal axis of the roller. The protuberance or projection 40 is 70 of such diameter and shape that it will extend into the open end of the can and uniformly engage the can so as to press the latter into true cylindrical form.

As a means for operating the correcting 75 roller 31, the shaft 32 is driven by a chain or sprocket arrangement generally designated 42, operatively associated with the sprocket 43 on the drive shaft 19. The sprocket arrangement is such that the roller 80 will be moved in synchronism with the movement of the conveyor 4 and blocks 22, whereby as each can is brought under the roller, the projection or protuberance 40 will extend into the open end of the can.

Mounted rearwardly of the roller 31 and in substantially the same horizontal plane therewith, is a similar cylindrical roller 44. This roller is mounted in the frame pieces 29 and 30 in the same manner as the other roller 90 and is adjustable in the same manner. The roller 44 is mounted upon a shaft 45 which is driven by a chain and sprocket arrangement 46 in turn operatively associated with the shaft 32. As the block containing the 95 can moves up to the roller 31, it brings the flange of the can into position to be engaged and ironed out on top of the blocks by the roller 44.

Assuming that the machine of my invention is installed adjacent to drainer and the syruping machine not shown, cans are placed in the conveyor by an operator and are carried by said conveyor so as to be operated upon by the machine of my invention. As 100 the cans engage the shoes 25 they are lifted upwardly and substantially coincident with their engagement with said shoes a pair of blocks 22 are brought into position to encompass and engage opposite sides of the can 105 with the flange of the can located above said blocks. The blocks thus engaged with the can, carry the latter beneath the roller 31 and when the can is so moved, the projection or protuberance 40 will extend into the upper end of the can and press said end into true cylindrical form thereby correcting any 110 irregularities of the can. The member 40 is so shaped that it will move into the can and press the same into proper shape at its 115 open end and then move out of the open end of the can as the roller 31 is rotated and the blocks 12 are advanced, the operation being continuous and not requiring cessation or 120 intermittent movement of the cans. The member 40 is primarily designed to correct irregularities in the body of the can but will serve in a measure to straighten out irregularities in the flanges as well. As the cans 125 move past the roller 31, the flanges 24 will be 130

engaged by the roller 44 and pressed against the upper flat surface of the blocks so that any dents or irregularities will be smoothed out and the flange will be made uniformly flat and right-angularly extended with relation to the body of the can. After the cans pass from the roller 44 and the blocks are moved apart in such manner that the can will be released and will be carried on to the next machine, the syruper, by the conveyor 4. It will be noted that throughout the operation of the machine, the conveyor serves to move the cans even when the latter are engaged by the blocks, inasmuch as in the latter case, the blocks and the conveyor are synchronized in their movement. By adjusting the rollers through the means described, the machine may be made to operate upon cans of differing heights and by use of different size blocks 22, cans of different sizes may be treated.

With my invention the troublesome, expensive and laborious system of smoothing out irregularities by hand is dispensed with and the canning operations are not materially prolonged, since the movement of the cans is a continuous one.

A can having irregularities at its end or its flange end such as a bent portion or a dent, when reaching the syruper will cause the syrup to run out over the side of the can and produce an undesirable condition in and around the syruping machine. Furthermore, such a can when reaching the sealing machine may not respond to the action of the sealing operation and produce a poor seal or seam which may be subject to rejection. These objections operate to produce losses in canning operations and are entirely overcome by employment of the device of my invention.

I claim—

1. A machine for correcting irregularities in cans having lateral flanges at the open ends thereof and preliminary to sealing the cans comprising a support, means for moving cans to and from the support, a rotary member on the support operating to engage and restore to normal shape the upper ends of cans passing beneath said member and during movement of the cans, said member having a projection adapted to extend into and press into true shape the open ends of the cans.

2. A machine for correcting irregularities in cans having lateral flanges at the open ends thereof and preliminary to sealing the cans comprising a support, means for moving the cans along the support, endless carriers mounted on the support on opposite sides of the path of the movement of the cans, members carried by the carriers and arranged to engage the cans as the latter are moved along the support with the flanges of the cans overlying said members, means for elevating the cans to dispose the flanges thereof above the plane of the upper sides of the can-engaging members at the time of engagement of the latter with said cans and a revolving member on the support arranged to engage the flanges of the cans as the latter are moved beneath said revolving member.

3. A machine for correcting irregularities in the lateral flanges at the open ends of cans preliminary to sealing the cans comprising a support, members between which the flanges of the cans are engaged, means for moving cans continuously in one direction to dispose the flanges between said members regardless of whether the flanges are bent downwardly or upwardly out of proper position and means for operating said members to smooth out irregularities in the flanges of the cans and restore said flanges to normal position during and without interrupting the progress of the cans.

4. A machine for correcting irregularities in the lateral flanges and in the bodies of cans adjacent said lateral flanges preliminary to sealing the cans, which machine includes a support, a member on the support having surfaces against which the portions of the cans containing irregularities are adapted to engage during the operation of correcting said irregularities, means for moving cans in position to so engage said member, a member between which and said surfaces the irregular portions of the can engage, and means operating said last named member to smooth out and correct irregularities in said cans, said last named member comprising a roller adapted to engage the flanges of the cans and having an annular protuberance thereon adapted to extend into the open ends of the cans.

GEORGE W. BLANKENHORN.
